(57) **CLAIM**

The ornamental design for an onion soup bowl, as shown and described.

DESCRIPTION

FIG. 1 is a perspective view of an onion soup bowl, showing my new design

FIG. 2 is a top perspective view thereof;

FIG. 3 is a top view thereof;

FIG. 4 is a bottom view thereof;

FIG. 5 is a right side view thereof; and,

FIG. 6 is a left side view thereof.

The broken lines in the drawings showing the bottom region of the onion soup bowl illustrate environmental matter and forms no part of the claimed design.
